UNITED STATES PATENT OFFICE

GODFRIED J. MAYER, OF BUFFALO, NEW YORK.

CARBURETER.

1,080,645.

Specification of Letters Patent.

Patented Dec. 9, 1913.

Application filed June 1, 1909. Serial No. 499,489.

To all whom it may concern:

Be it known that I, GODFRIED J. MAYER, a citizen of the United States, residing at Buffalo, in the county of Erie and State of New York, have invented certain new and useful Improvements in Carbureters, of which the following is a specification.

My invention relates to improvements in carbureters, such as are used in connection with explosive-engines whereby a suitable explosive mixture is obtained to provide the necessary power for operating the engine.

The object of my invention is the production of a simple and efficient carbureter of this type, by means of which the suction induced by the engine acts upon a series of valves arranged to unseat by atmospheric pressure under different degrees of suction, so that when the engine runs at a low speed, only a portion of said valves become unseated, while as the engine increases in speed, the suction action also increases and acts to open some or all of the remaining valves of the series.

It also has for its object the provision of a diaphragm or wall provided with a number of openings of different sizes in which are seated balls or globular members serving as valves and having different areas exposed to the atmospheric air so that under the different running conditions of the engine, the valves will unseat accordingly and allow the proper quantity of air to enter the mixing-chamber for the purpose of providing, at all times, an explosive mixture having the proper proportion of air and gasoline.

Other objects are to provide a removable sleeve in which is located the exit-end of the aspirating-nozzle and surrounding which is a series of valves arranged to open under different speeds of the engine so that the air is admitted to the mixing-chamber of the carbureter in increased quantities as the engine increases and so that the gasoline is drawn from the aspirating-nozzle in corresponding quantities; said sleeve being adapted to be replaced by another having a different size bore, the size of which depends to a certain extent on the engine and the amount of air to be drawn over the end of the aspirating-nozzle for best results.

A still further object of my invention is to improve on carbureters now in use; and to these ends it consists in the construction, arrangement, and combination of parts to be

hereinafter described and particularly pointed out in the subjoined claims.

In the drawings.—Figure 1 is a side elevation of a carbureter constructed according to my invention. Fig. 2 is a central vertical section through the carbureter proper and a portion of the gasoline feed-chamber connected thereto. Fig. 3 is a horizontal section taken on line 3—3, Fig. 2. Fig. 4 is a vertical section taken on line 4—4, Fig. 2. Fig. 5 is a horizontal section looking up, taken on line 5—5, Fig. 2, the aspirating-nozzle being omitted. Fig. 6 is a plan view of the diaphragm or disk in which are formed the valve-seats for the globular valves. Fig. 7 is a detached perspective view of the reducing sleeve into which the delivery or exit-end of the aspirating-nozzle projects.

Referring now to the drawings in detail, like letters of reference refer to like parts in the several figures.

The reference letter A designates a gasoline feed-chamber of any common construction, so arranged that it will feed gasoline into the carbureter-proper B and maintain the same at a constant level; said gasoline feed-chamber having a threaded extension a adapted for connection with said carbureter. As is common in gasoline feed-devices of this character, a suitable controlling-valve is employed to govern the flow of gasoline to the carbureter.

In the preferred form, the carbureter comprises two sections C and D; the section C being at the lower end thereof and preferably of tubular construction and of substantially U-formation. The section C may, however, be of any other formation so long as it provides for the introduction of air into the carbureting-chamber. The section D is mounted on the section C and for the purpose of connecting the same to section C in a rigid manner, said sections have cooperating-flanges c, d, through which screws d¹ are passed. Held between the two sections of the carbureter is a disk E serving as a diaphragm or wall and having centrally therein a threaded opening e into which fits an externally threaded strangling or reducing-sleeve F provided at its upper end with a stop-flange f adapted to bear against the upper side of said disk; said sleeve extending through said disk a short distance so as to enter the air-chamber G formed by the

lower section C of the carbureter, and itself serving as the carbureting-chamber. Extending upward from said stop-flange are retainer-lugs f^1 , for a purpose to appear 5 hereinafter.

An aspirating-nozzle H is provided which 10 preferably has connection with the extension a of the gasoline feed-chamber and from its point of connection thereto is directed inward and upward so that its exit-end terminates 15 centrally within said reducing-sleeve. The disk or wall E is provided with a circular series of openings I of different diameters which are beveled to serve as valve-seats for a series of globular valves J of 20 equal size and weight normally held in their seats and adapted to be lifted by the atmospheric air for the purpose of uncovering said openings to allow air to pass there-

The upper section D of the carbureter 25 serves as the mixing-chamber and is enlarged at its lower end to provide an annular shoulder K which serves as a stop to limit the upward or opening movement of 30 said globular valves. The upper end of said section is threaded for connection thereto of a pipe leading to the ignition-chamber of the engine and for the purpose of heating 35 the interior of the mixing-chamber, a removable jacket L is threaded onto said section. Threaded bosses l, l¹, extend from said jacket, to which pipes may be connected for providing a circulation therethrough of a 40 suitable heating agent. A throttle-valve M in the form of a disk, is pivotally held within the upper section of the carbureter, a short distance above the disk or wall E and its stem m which passes through the wall of 45 said section, as at m¹, has a manipulating-lever N secured thereto to which may be attached a rod or other suitable means for actuating it from a distant point. Said lever has a toe n which is adapted to strike 50 a screw O adjustable in a stop O¹ extending outward from the section D so as to limit the movement of the valve in one direction; said stop being so positioned with relation to the axis of said lever that the latter 55 strikes the same adjacent its axis to limit the movement of the throttle-valve in its opposite direction.

The operation of the device is as follows:—When the engine is to be run at low 60 speed, the manipulating-lever N is in the position shown in Fig. 1, with the toe thereof against the stop O and the throttle-valve assuming the position shown in Fig. 2, leaving just sufficient space between its edge and the wall of the mixing-chamber, as at P, to 65 permit the engine, when turned over by hand, to create a vacuum or at least a partial vacuum in the space between said throttle-valve and the exit-end of the aspirating-nozzle, thus permitting the air to rush into

said space from the lower section of the carbureter and draw a small charge of gasoline from the aspirating-nozzle. The air in the lower section of the carbureter acts at the same time upon the exposed portions of the globular valves seated in the largest opening or openings I and slightly lifts the same to permit the air to pass up through said openings and commingle with the air passing through the reducing-sleeve and the vaporized gasoline drawn from the aspirating-nozzle, the air and gasoline becoming thoroughly mixed and passing up between the throttle-valve and the wall of the mixing-chamber and passing out through the top of the carbureter to be drawn into the engine where the charge is ignited to propel the engine. A slight opening movement of the throttle-valve will create increased suction upon the aspirating-nozzle and cause an increased volume of air to be drawn through the reducing-sleeve, which air and the supply of gasoline passing upward through the reducing-valve are also supplied with an additional quality of air passing up through additional openings I in the disk or wall E, due to the fact that the increased pressure of the air in the chamber G will cause an additional globular valve or valves to become unseated. A further increased supply of air and gasoline is obtained upon further opening of the throttle-valve, until the engine is permitted to run at high speed. The closing of the throttle-valve will immediately cause a reduction in the supply of air and gasoline in proportion to the extent to which said valve is closed, so that the mere manipulation of the throttle-valve will govern the speed of the engine after the same is set into motion. When the globular valves J rise from their seats, they are guided and retained in alignment with their seats by the retainer-lugs f.

By reason of the openings in the disk or wall E being of different sizes, different areas of the valves are exposed through the bottom of the same so that the air-pressure in the lower section acts first to elevate the valve or valves having the greatest area exposed and as the air-pressure increases, owing to the suction action in the carbureting-chamber increasing, the globular valves having the next greater area exposed are caused to rise. This being continued with the increased pressure of the air until all of the globular valves are unseated, or until the engine runs at highest speed. The number of valves unseated are therefore always in proportion to the speed of the engine, thus assuring at all times a proper mixture of air and gasoline.

For some types of engines, the area of the reducing sleeve F shown in the accompanying drawings, may be too large for best results, in which case it is simply necessary to

separate the two sections of the carbureter, remove the disk with the globular valves thereon and replace the reducing-sleeve by a sleeve having a smaller bore, after which the 5 disk may be properly seated and the two sections connected.

The construction herein shown provides for the use of a disk having openings therein and valves closing said openings; said disk 10 being fully confined within the casing of the carbureter and serving as a diaphragm or wall through which the gasoline and the entire supply of air must pass in order to reach the ignition-chamber of the engine.

15 Having thus described my invention, what I claim is.

1. In a carbureter, the combination with a casing having an air-inlet and a mixture-outlet, a horizontal wall located between 20 said inlet and said outlet and provided with a central opening and a circular series of openings of different diameters surrounding said central opening, globular valves of equal diameter held by gravity in said circular series of openings, a reducing-sleeve removable in said central opening, an aspirating-nozzle extending into and terminating within said reducing-sleeve, and a throttle-valve between said aspirating-nozzle and 25 said mixture-outlet.

2. In a carbureter, the combination with a casing having an air-inlet and a mixture-outlet and divided transversely between said inlet and outlet to provide two connected 35 sections, one of which is enlarged at its connected end to provide an internal shoulder, of a disk held between said sections and having a central threaded opening and a circular series of valve openings of different 40 diameters surrounding said central opening, globular valves of equal diameter seated in

said valve-openings and limited in their opening movement by said internal shoulder, a reducing sleeve in said central opening, an aspirating-nozzle terminating within said 45 reducing-sleeve, and a throttle-valve between said aspirating-nozzle and said mixture-outlet.

3. In a carbureter, the combination with a casing having an air-inlet and a mixture-outlet and divided transversely between said 50 inlet and outlet by a horizontal wall provided with a central opening and a circular series of valve-openings surrounding said central opening, globular valves seated in 55 said valve-openings, a reducing-sleeve removable in said central opening and having upstanding retainer elements guiding said globular valves and retaining them in alignment with said openings, an aspirating-nozzle terminating within said reducing-sleeve and a throttle-valve between said 60 aspirating-nozzle and said mixture-outlet.

4. In a carbureter, the combination with a casing having an air-inlet and a mixture-outlet, of a wall dividing said casing into two chambers and having a central threaded opening and a series of valve-openings, gravity valves of equal size closing said 65 valve-openings, a sleeve threaded into said central opening, an aspirating-nozzle terminating within said sleeve, and a throttle-valve between said aspirating-nozzle and 70 said mixture-outlet.

In testimony whereof, I have affixed my 75 signature in the presence of two subscribing witnesses.

GODFRIED J. MAYER.
